[57] CLAIM

The ornamental design for golf practice putting aid, as shown and described.

DESCRIPTION

FIG. 1 is a perspective view of a golf practice putting aid showing my new design;

FIG. 2 is an elevational view of one of the support members thereof;

FIG. 3 is an elevational view of a second support member thereof;

FIG. 4 is a side elevational view thereof;

FIG. 5 is a top plan view thereof; and,

FIG. 6 is a bottom plan view thereof.

The putter is shown in broken lines for illustrative purposes only. The string is of indeterminate length.

The dotted lines are shown for illustrative purposes only.
